VINCENT J. POWER, OF PRATT, KANSAS, ASSIGNOR OF ONE-TWENTIETH TO B. HARMS,
OF MCPHERSON, KANSAS.

RIVETING BAR.

1,414,095.

Specification of Letters Patent. Patented Apr. 25, 1922.

Application filed February 11, 1921. Serial No. 444,250.

To all whom it may concern:

Be it known that I, VINCENT J. POWER, a citizen of the United States, residing at Pratt, in the county of Pratt, State of Kansas,

5 have invented a new and useful Riveting Bar; and I do hereby declare the following to be a full, clear, and exact description of the invention, such as will enable others skilled in the art to which it appertains to 10 make and use the same.

The invention relates to riveting bars and has for its object to provide a device of this character, particularly adapted for insertion between the flanges of a channel bar for 15 holding rivets in either flange of the channel bar during a riveting operation and is particularly designed for use in connection with automobile frames wherein channel bars are used.

20 A further object is to provide a rivet holding bar comprising a handle member having a right angled portion, the under face of which is provided with a transversely disposed groove for engaging and holding one or more rivet heads during a riveting operation. The upper side of said angularly disposed portion being adapted to engage rivet heads for holding rivets during a riveting 25 operation, when said heads are so disposed that they cannot be conveniently held in the transversely disposed groove. Also to provide a transversely disposed groove adjacent the heel of the bar for cooperating with one 30 of the flanges of the channel bar.

35 With the above and other objects in view the invention resides in the combination and arrangement of parts as hereinafter set forth, shown in the drawings, described and claimed it being understood that changes 40 in the precise embodiment of the invention may be made within the scope of what is claimed without departing from the spirit of the invention.

In the drawings:—

45 Figure 1 is a perspective view of a portion of an automobile frame, showing the riveting bar in position thereon.

Figure 2 is a detail perspective view of the lower end of the riveting bar.

50 Figure 3 is a detail sectional view through

a channel bar of an automobile frame, showing the riveting bar in position for holding a rivet in the upper flange of the channel bar.

Referring to the drawings, the numeral 1 designates the bar which may be of any length desired, and 2 the handle thereof. The lower end 3 of the bar is provided with an angularly disposed member 4, the under face 5 of which is provided with a transversely disposed groove 6, adapted to receive and engage rivets 7 which pass through the lower flange 8 of the channel bar 9 of the automobile frame. The transversely disposed groove 6 is of sufficient length to engage a number of adjacent rivets at the same time thereby holding the rivets when any of them are being riveted. When it is desired to hold rivets in the flange 10 of the channel bar 9, the heel 11 which is provided with an angularly shaped groove 12 is placed in engagement with the lower flange 8 adjacent its edge, and the bar rocked on the same until the upper face 13 of the member 4 engages the rivet 14 in the upper flange 10 thereby holding said rivet during a riveting operation. By referring to Figure 3, it will be seen that when the riveting bar is forced downwardly at its handle end that as much pressure as is desired may be applied to the rivet 14, and it will also be seen that the edge 15 of the flange 8 of the channel bar will be received by the rectangular groove 12 in the heel 11 in such a manner as to prevent inward slipping of the lower end of the bar during a rivet holding operation.

From the above it will be seen that a riveting bar is provided which is particularly adapted for holding rivets in flanges of channel bars, particularly automobile frames, in such a manner that rivets may be easily held during riveting operations.

The invention having been set forth what is claimed as new and useful is:—

A rivet holding bar comprising an elongated member forming a handle, the lower end of said handle terminating in a substantially right angled portion forming a rivet engaging and holding member, the lower face of said rivet holding member being pro-

95

100

vided with a transversely disposed groove extending entirely across the same, the heel of the rivet holding member being provided with a transversely disposed groove adapted to engage a flange of a channel bar during a rivet holding operation.

5 In testimony whereof I have signed my

name to this specification in the presence of two subscribing witnesses.

VINCENT J. POWER.
